(57) **CLAIM**

The ornamental design for a tower merchandiser, as shown and described.

DESCRIPTION

FIG. 1 is a perspective view of the tower merchandiser, in accordance with the design;

FIG. 2 is a front view of the tower merchandiser of FIG. 1; FIG. 3 is a rear view of the tower merchandiser of FIG. 1; FIG. 4 is a right side view of the tower merchandiser of FIG. 1; and,

FIG. 5 is a top plan view of the tower merchandiser of FIG. 1.

The portions of the tower merchandiser shown as broken lines are for illustration purposes only and do not form part of the design.

1 Claim, 1 Drawing Sheet
